UNITED STATES PATENT OFFICE.

JAMES JOSEPH GORMAN, OF CINCINNATI, OHIO.

IMPROVEMENT IN OBTAINING AND TRANSMITTING POWER.

Specification forming part of Letters Patent No. 43,768, dated August 9, 1864.

To all whom it may concern:

Be it known that I, JAMES JOSEPH GORMAN, of Cincinnati, in the county of Hamilton and State of Ohio, have invented a new and Improved Mode of Obtaining and Transmitting Power; and I do hereby declare that the following is a full, clear, and exact description of the same, reference being had to the accompanying drawings, forming a part of this specification, in which—

Figure 1 represents a side elevation of my invention. Fig. 2 is a longitudinal vertical section of the same. Fig. 3 is a plan or top view of the same. Fig. 4 is a diagram showing the means employed for overcoming the dead-centers. Fig. 5 is a modification of the same.

Similar letters of reference in the several views indicate corresponding parts.

This invention consists in the application of two weights suspended from or secured to arms, which project from an oscillating frame with a variable fulcrum, in combination with a rolling or movable weight, which moves on inclines and is made to bear alternately on the oscillating frame in such a manner that by the aid of the variable fulcrum and movable weight the oscillating motion of the frame and two main weights is facilitated and a power is obtained capable of imparting motion to a hoisting apparatus or to any other desirable machine or mechanism.

The invention consists, further, in the employment or use of automatically rising-and-falling guideways, in combination with the oscillating frame, movable or rolling weight, and with a stationary frame, in such a manner that by the action of the guideways the movable weight is made to bear alternately on the oscillating frame and then again on the stationary frame, and thereby the motion of said oscillating frame is facilitated.

The invention consists, further, in a dog, hinged to the rod or pitman, which transmits the motion of the oscillating frame to the working machine, said dog being provided with two studs, in combination with a cam furnished with two or more cavities corresponding in position to the studs of the dog and secured to the end of the shaft to which the motion is to be transmitted, and with a spring acting on the dog in such a manner that whenever the pitman arrives at one of

the dead centers the position of the dog in relation to the cam is changed by the action of the spring, and the dead center is avoided in the simplest and most effective manner.

The invention consists, finally, in combining the spring and the hinged dog with a rocker-arm and with a lever catching on eccentric wrist-pins projecting from a disk secured to the shaft, to be driven on opposite sides from its center in such a manner that by a simple change in the position of said lever from one pin to the other the motion of said shaft can be reversed without changing the motion of the oscillating frame.

To enable those skilled in the art to make and use my invention, I will proceed to describe it.

A represents a frame, made of wood or any other suitable material, and composed principally of two side pieces, *a*, the upper edges of which are provided with notched plates *b*, which support the knife-edge bearings *c c' c''* of the oscillating frame *B*. This frame is made of metal or other suitable material, and it consists of two side pieces, *c'*, which are connected to each other by cross-bars *d*, and each of which is supported by three knife-edge bearings, *c c' c''*, as above stated. On imparting an oscillating motion to the frame *B* its fulcrum changes from one of the bearings to the other, and it is obvious that if the frame is in equilibrium and supported by the middle bearing, *c'*, the balance will be immediately destroyed when said frame is brought in an inclined position so that it rests on one of the bearings *c* or *c''*.

C' are two arms which project from the frame *B* in opposite directions, being made adjustable by means of set-screws, so that they can be drawn out or pushed in, as may be desirable. Secured to outer ends of these arms are two heavy weights *D D'*, which oscillate with the frame *B* and impart to the oscillations of the same a certain momentum or living force capable of overcoming obstructions or of doing some work. A spring, *d**, which is connected with one end to an arm, *D**, projecting from the main frame *A* and with the other end to the end of the oscillating frame *B*, serves to ease the motion of the weight *D D'* and to prevent undue strain at either end of the stroke. If the weight *D'* descends in the direction of the arrow marked near it in

Fig. 1, the bearings $c c'$ are relieved and the whole pressure exerted by the frame B and weight D D' is supported by the bearings c'' , and if the weights D D' at the beginning of the operation are equally balanced on the middle bearings, c , it is obvious that the balance is destroyed as soon as the fulcrum is transferred from the central bearings to the bearings c'' . As soon as this takes place the weight D overbalances the weight D' and the motion of the frame B is reversed. Motion is imparted to the frame and weights D D' by means of a crank-shaft, e , which may be rotated by hand or other competent power, and which connects by a rod or pitman, e , with said frame, and its motion is facilitated by the action of a rolling weight, E. The axle of this weight passes through two arms, f , which are connected to the ends of a pin, f' , that has its bearings in the upper end of the arm g of a double-elbow lever $g g' g''$, and said axle is supported by two double-treaded or hard-faced wheels h . The double-elbow lever $g g' g''$ has its fulcrum on a pivot, g^* , which is firmly inserted in the inner surface of one of the side pieces of the main frame A, and the arms $g' g''$ are of unequal length and curved, as clearly shown in Fig. 2. They are loaded with weights and, by reason of the unequal length of the arms $g' g''$ and of their peculiar shape, they cause the rolling weight E to travel up the inclined guideways i on one and the incline g^5 on the opposite side, and thereby assist in producing and keeping up the oscillating motion of the frame B and weight D D'. A rod, g^4 , connects the elbow-lever with that end of the frame B nearest to the weight D', and the motion of said frame is thereby communicated to it. If the machine is at rest or if the oscillating frame B with the weight D D' is placed in a horizontal position, the rolling weight places itself beyond the center of the frame B toward the weight D, as shown in Figs. 1, 2, and 3 of the drawings, and its wheels rest on guideways i , which are supported by the curved edges of the frame B and project over the same sufficiently far to reach the wheels h , said wheels being placed so close together that they pass freely down between the frame B. The guideways i are pivoted to a stirrup, i' , which embraces the frame B, being attached to the same by means of pivots i^* , and it is subjected to the action of a spring, i'' , which has sufficient power to raise those ends of the guideways i nearest to the weight D whenever said guideways are relieved from the pressure of the rolling weight E. If the crank-shaft e is turned in the direction of the arrow marked near it in Figs. 1 and 2, the weight D descends and the rolling weight E passes up the inclined guideways i , bearing down upon the frame B and assisting in throwing said frame from the central bearing, c , on the bearing e . As soon as the rolling weight E passes beyond the guideways i the wheels h drop down upon the stationary frame G, and said guideways being relieved from pressure

are raised by action of the spring e'' and brought in such a position that the wheels h of the rolling weight can pass back under the same without obstruction. The stationary frame G projects up between the oscillating frame B, being supported by arms g^3 , which are rigidly attached to the main frame A, and it is obvious that when the weight D has descended low enough to throw the wheels of the rolling weight upon the stationary frame G the effect of said rolling weight on the oscillating frame ceases, and the weight D' descends with considerable force, due to the difference in the distance of the two weights from the bearings c , which support the oscillating frame B at the moment it is relieved from the action of the rolling weight E. The momentum of the weight D', which it acquires by the time it reaches a horizontal position, carries the same down and throws the fulcrum of the oscillating frame upon the bearings c'' , and at the same time, by the action of the rod g^4 on the elbow lever $g g' g''$, the rolling weight E is carried up the inclined plane g^5 at the end of the stationary frame G nearest to the weight D', and by the time said weight D' has reached its lowest point the rolling weight E reaches its highest point on the inclined plane, ready to descend with some force. In this position the fulcrum of the frame B is on the bearings c'' , and the weight D, being further from said bearings than the weight D', will descend with considerable force, assisted by the rolling weight E, which descends over the incline g^5 and ascends the curved guideways i , which will be depressed on the edges of the frame B and take up the pressure of the wheels h . The momentum of the weight D, acquired by the same, by the time it reaches a horizontal position, assisted or augmented by the action of the rolling weight E, bearing down upon the frame B, carries said weight D down, the fulcrum changes from the bearings c'' to the bearings c , and the weight D' rises. In this manner the motion of the weights D D' and rolling weight E is continued, and the motion desired by this arrangement is transmitted by means of a rod or pitman, H, dog I, and cam J to the shaft K. The dog I is attached to the loose end of the pitman H by means of a pivot, j , and it is provided with two studs, $k k'$, which catch into corresponding cavities $l l' l^* l^*$ in the cam J. This cam is firmly secured to the end of the shaft K, which may be provided with a drum to receive the hoisting-rope, or, through the action of which, motion may be transmitted to the working machines. The cavities $l l' l^* l^*$ are equidistant from the center of the shaft K, and either one pair or the other may be brought in working position.

In the drawings, the dog is shown in contact with the cavities $l l'$, and the cavities $l^* l^*$ are held in reserve, to be used alternately with the cavities $l l'$, as may be desired. The distance of the cavities $l l'$ from the center of the shaft K or the stroke of the cam J may either be made equal to or smaller than the

stroke of the frame B, but in no case can it be made larger. In Figs. 1, 2, and 4 of the drawings the stroke of the cam is equal to that of the oscillating frame, but in Fig. 5 it is larger. The dog I connects, by means of a rod, L, with a rocker-arm, M, which has its fulcrum on a pivot, m, in a bracket, N, that is firmly secured to the main frame A, and as the cam J revolves an oscillating motion is imparted to the rocker-arm by the action of the rod L, and its ends, which are armed with friction-rollers m', strike a spring, O, which is secured to a small rock-shaft, o, having its bearings in the outer ends of the bracket N. This rock-shaft carries a crank, p, which connects, by means of a hooked rod, P, with one or the other of the eccentric wrist-pins q q', projecting from the outer surface of a disk, Q, which is secured to that end of the shaft K opposite the cam J. These wrist-pins are arranged on opposite sides of the center of the shaft K, and by changing the position of the hooked end of the rod P from one wrist-pin to the other the motion of the shaft K is reversed without changing or reversing the motion of the crank-shaft e or that of the oscillating frame B. By the action of the spring O on the ends of the rocker-arm M the dog I is always brought in such a position in relation to the cam J that the dead centers are entirely avoided, and the motion from the oscillating frame B can be transmitted to the shaft K by a continuous direct application of the driving-power and entirely without the aid of a fly-wheel or equivalent means. If the stroke of the oscillating frame B is longer than that of the cam J, the dog e will assume a position such as shown in Fig. 5 whenever the frame passes the extreme points of its motion; but if the stroke of the frame B is equal to the stroke of the cam J the dog I will be in the position shown in the Figs. 1, 2, and particularly in Fig. 4. When that end of the frame B which connects with the dog J has reached its highest point, the dog is raised or its position changed by the action of the spring, so that the stud K touches the bottom of the cavity l and the stud k' bears against the inner side of the cavity l', and by this action the connection-rod or pitman is thrown beyond its dead-center and the motion of the machine

continues without interruption, and no fly-wheel is needed to pass the dead-center.

It must be remarked that the connecting-rod or pitman H, instead of being connected to the oscillating frame B, might equally well be connected to the cross-head of an ordinary steam-engine, and the reciprocating motion of the steam-piston can thus be converted into continuous rotary motion of the shaft B. The motion of the shaft K is reversed by changing the hooked end of the rod P from the eccentric wrist-pin q to the pin q', as previously stated, and by doing so the position of the spring O in relation to the rocker-arm is changed, and thereby the action of said spring on the dog is reversed, causing the same to pass the dead-centers in the direction opposite to that in which it acted before, and by these means the shaft K is caused to rotate in the opposite direction.

What I claim as new, and desire to secure by Letters Patent, is—

1. The variable fulcrum c c' c'', in combination with the oscillating frame B, carrying the weights D D', and with the rolling weight E, constructed and operating in the manner and for the purpose substantially as herein shown and described.

2. The weights g'* g***, arranged in combination with the rolling weight E, automatically rising-and-falling guideways i, stationary frame G, and oscillating frame B' with weights D D', all constructed and operating in the manner and for the purpose substantially as set forth.

3. The dog I, spring O, and rocker-arm M, and cam J, with cavities l l', in combination with the oscillating frame B, or its equivalent, and with the shaft K, constructed and operating substantially as and for the purpose set forth.

4. The spring O and rock-shaft o, in combination with the hooked rod P, eccentric wrist-pins q q', dog I, cam J, shaft K, and oscillating frame B, or its equivalent, constructed and operating in the manner and for the purpose substantially as described.

JAMES JOSEPH GORMAN.
